DESIGN FOR A HANDBAG

Edwin B. Nathan, Bronx, N. Y.

Application June 9, 1948, Serial No. 146,844

Term of patent 7 years

(Cl. D87—3)

To all whom it may concern:

Be it known that I, Edwin B. Nathan, a citizen of the United States and a resident of New York, county of Bronx and State of New York, have invented a new, original, and ornamental Design for a Handbag, of which the following is a specification, reference being had to the accompanying drawing, forming part thereof.

In the drawing:

Fig. 1 is a front perspective view of a handbag embodying my new design;

Fig. 2 is a rear perspective view of the handbag;

Fig. 3 is a bottom plan view thereof;

Fig. 4 is a side elevational view thereof;

Fig. 5 is a front perspective view similar to Fig. 1 with the pocket element in a raised position;

Fig. 6 is a front elevational view of the handbag in an open position; and

Fig. 7 is a perspective view of the removable article holding element.

I claim:

The ornamental design for a handbag, as shown.
EDWIN B. NATHAN.
